Atty.

UNITED STATES PATENT OFFICE.

HARRY T. BROCKMAN, OF CLEVELAND, OHIO.

DESIGN FOR A PATRIOTIC EMBLEM, PIN, OR BUTTON.

51,688.

Specification for Design. Patented Jan. 15, 1918.

Application filed November 16, 1917. Serial No. 202,420. Term of patent 3½ years.

To all whom it may concern:

Be it known that I, HARRY T. BROCKMAN, a citizen of the United States, residing at Cleveland, in the county of Cuyahoga and State of Ohio, have invented a new, original, and ornamental Design for a Patriotic Emblem, Pin, or Button, of which the following is a specification, reference being had to the accompanying drawing, forming part thereof.

The figure is a plan view of a pin or button showing my new design.

I claim:

The ornamental design for a patriotic emblem pin or button, as shown.

HARRY T. BROCKMAN.
